UNITED STATES PATENT OFFICE.

NEWTON J. DARDEN, OF WASHINGTON, DISTRICT OF COLUMBIA.

NECKTIE HOLDER.

Application filed October 7, 1922. Serial No. 593,058.

To all whom it may concern:

Be it known that I, NEWTON J. DARDEN, a citizen of the United States, residing at Washington, in the District of Columbia, 5 have invented new and useful Improvements in a Necktie Holder, of which the following is a specification.

This invention comprises a necktie holder. It is contemplated by this invention to provide a device that may be used in connection with collars of different styles and widths which may be quickly placed in position by buttoning it to the collar button; and that will carry a tie detachably arranged on a 15 detachable spring member of the device in such a way that the tie carrying portion may be changed at will without renewing that portion which is secured to the collar; and whereby the tie-carrying portion may be 20 utilized to carry various forms of ornaments, such as rosettes, jewelry, ribbon, ornamental devices or other desirable substitutes for neckwear; also of such form that the necktie holder may be used with collars of the soft, 25 folded, or standing varieties.

Another object is to construct the necktie holder component which is to be secured to the collar, of such material that it will be stiff yet sufficiently pliable and moisture-proof, to conform to the shape of the collar, and to provide it with an attaching tab which will securely grip the collar button and support the tie outwardly from the collar and at the same time will be conformable to the 30 movements of the body and will be adjustable for use with various heights of collar; and to make the tie-carrying spring component of resilient material other than metal, thus eliminating the rust, rattling and 35 piercing the cloth of the collar which attends use of metal parts in this connection.

Other objects and advantages will be evident in part and in part disclosed more fully in the description which follows:

45 Certain embodiments of the invention are illustrated in the accompanying drawing, the following views being shown:

Figure 1 is a view in front elevation of a tie holder embodying my invention;

50 Fig. 2 is a view of the same in longitudinal section on line 2—2 of Fig. 1;

Fig. 3 is a view of the same in vertical section, on line 3—3 of Fig. 1;

55 Fig. 4 is a view in perspective showing a carrying component with a tie attached;

Fig. 5 is a view in front elevation of a

modified form of holder used with standing collars;

Fig. 6 is a view in perspective of the obverse side of a carrying component with bow 60 tie attached;

Fig. 7 is a view in front elevation showing a carrying component with an ornamental rosette attached; and

Fig. 8 is a view in front elevation of a 65 carrying component itself.

In these views 1 designates generally a body portion and 2 an attaching tab comprising one component of the holder. These include, in the present instance, a foundation or reinforcement 3 of resilient composition, such as rubber stiffened by fabric 4 embedded in the rubber or otherwise made a part of it so that the foundation will be pliable and springy. The fabric stiffening 70 may be and preferably is of texture and surface composition such as will make a clean and easily washed covering for the base rubber, and embedded on both surfaces of the rubber it performs the double function 75 of acting as a stiffening or reinforcing agent for the rubber and as a suitable finish for this part of the holder itself.

The base portion is tapered toward its 85 outer extremities forming thinned out end portions 5, and gradually increases in thickness towards the center to constitute a reinforced or thickened portion 6 disposed centrally of the body portion and extended down into the securing tab. This arrangement permits ready adjustment of the elastic body portion to the curvature and movement of the neck of the wearer, and the utilization 90 of rubber or like composition in the tab permits a desired gripping action of button holes 7 around a button 8, best shown in Fig. 3. These holes in the tabs arranged in spaced relation to collar widths constitute an adjustable means of securing the body 95 of the holder to any collar, and when used in the position shown in Fig. 3, a cushion or bulged out portion 9 is formed which acts as a support for a thin tie, when desired, holding it outwardly from the collar and bosom of the shirt.

100 The body portion is provided with folded-over flaps or members 10 which form pockets for the reception of the other component of the device. This comprises a carrying member 11 formed from some flexible springy material such as celluloid or pressed, hardened rubber which is bowed to conform to 105

shape of the wearer's neck. It is made of slightly greater length than the space between the ends of the pockets on the body portion so that when inserted therein as shown in Figs. 1 and 5, it will stretch and stiffen the body portion; and the center portion of the carrying member will be bowed outwardly in spaced relation to the body portion as seen in Fig. 2. This arrangement 10 provides a space for the insertion of a portion of a tie; and to prevent the tie from sliding longitudinally on the carrying member there is a recessed or cut-out portion 12 in an edge of the carrying spring member. 15 This member is also provided with holes 13 for the insertion of means for securing it to any desired attachment, stitches 15, and a bow tie being shown in Fig. 6. Another opening 16 provides a means for securing any desired form of ornament to the spring-carrying member, a rosette 17 being indicated in Fig. 7, and having a centrally disposed securing means 18 inserted in the 20 central opening in the spring-carrying member. 25

When used with a standing collar, the tab portion is shortened or even dispensed with entirely as shown in Fig. 5; and there is provided, at the ends of the body portion, securing means 19 for attachment to an elastic band 20, a portion only of which is shown in said figure, and which band is adapted to encircle the neck. In the present instance, the fastening means comprises a socket snap member secured to the body portion, thus providing a flat face with a head member on the band cooperating with the socket on the body portion; and the elastic securing means when removed permitting the tie holder to 30 be used in the usual manner with turn-down collars. 35

The invention thus comprises a simple, practical and inexpensive means of accomplishing the objects set forth. While the embodiment herein shown has been disclosed as the preferred form of the invention, it will be understood that certain variations in the construction, materials and arrangement of the parts are considered to be within 45 the scope of the invention as set forth in the claims. 50

What I claim is:

1. A tie holder comprising a plurality of components, one component including a body portion provided with a pocket thereon; a securing tab associated with the body portion and provided with means for attaching it in place; and another component comprising a tie carrying member adapted to be disposed in the pocket and provided with means for securing a tie or the like thereto. 55

2. A tie holder comprising a plurality of

components, one component including a body portion provided with a pocket thereon; a securing tab associated with the body portion and provided with means for attaching it in place; another component comprising a tie carrying member adapted to be disposed in the pocket and provided with means for securing a tie or the like thereto; and a base 65 formed from resilient composition reinforcing the body and tab. 70

3. A tie holder comprising a plurality of components, one component including a body portion provided with a pocket thereon; a securing tab associated with the body portion and provided with means for attaching it in place; another component comprising a carrying member adapted to be disposed in the pocket and provided with means for securing a tie or the like thereto; and a base 75 formed from resilient composition reinforcing the body and tab, said base being thickened at its central portion and gradually tapered in thickness from this point towards the ends thereof. 80

4. A tie holder comprising a body portion formed from resilient material impervious to moisture; a reinforcing element disposed centrally of the body portion and tapered 90 gradually toward the ends thereof; a securing tab on the body portion; a reinforcing element of elastic composition forming a part of the securing tab; said tab being provided with means for attaching it in place; members on the body portion in spaced-apart relation, forming a pocket; a carrying member to which an ornamental device is adapted to be secured, associated with the body portion, said carrying member comprising a resilient body of slightly greater 95 length than the space between the members forming the pocket and having a central portion bowed outwardly in spaced relation 100 to the body when the ends of the carrying member are disposed in the pocket, and means for holding an ornamental device thereon. 105

5. A tie holder comprising a plurality of components, one component including a body portion provided with a pocket thereon; a securing tab provided with a plurality of spaced-apart openings therein for attaching it in place, associated with the body portion; and another component comprising a tie carrying member adapted to have a portion thereof disposed in the pocket when in place, said securing tab being formed in part from resilient composition whereby it may be bent 110 to constitute a means for forcing a tie outwardly from the body portion. 115

In testimony whereof I affix my signature.

NEWTON J. DARDEN.
